UNITED STATES PATENT OFFICE

2,600,635

HOSIERY MENDING MACHINE

Charles W. Gardner, Glenside, Pa., assignor, by
mesne assignments, to Prestige, Incorporated,
New York, N. Y., a corporation of Pennsylvania

Application June 8, 1948, Serial No. 31,820

1 Claim. (Cl. 38—36)

1

In the knitting of stockings, and other articles, from synthetic threads, it often happens that one or more threads may be snagged, and more or less pulled. A thread so snagged, and some of the threads adjacent thereto, will be stretched and otherwise distorted, and in order to ameliorate this damage, it has been the practice to spread the damaged portion of the stocking over the mouth of a cup, or similar support, and then to work the thread or threads back into their original position, by manipulating the displaced threads with a dull instrument. However, after this is done, and no matter how expertly it is done, the stretched and distorted threads will leave a wrinkle or other defect. Such stockings or other articles can only be sold as defective or as seconds and therefore at a considerable loss.

It is therefore the main object of the invention to produce an improved method and an improved apparatus for eliminating the wrinkles or other marks remaining after snagged threads have been worked back into position in the manner above set forth, thus making it possible to upgrade such stockings or, possibly, to sell them as regular goods.

To reset synthetic yarns, that is, to bring them back, as nearly as possible, to their original shape, involves the application of controlled heat and pressure. The heat must be sufficient to soften but not to melt the threads and the pressure must be such as to cause the heated thread to "run" or "flow" but not such as to create new distortions or to leave new marks on the fabrics treated.

It is therefore a further object of the invention to produce an improved apparatus whereby the desired heat and pressure are applied in a manner to insure satisfactory results.

These and other objects are attained by my invention as set forth in the following specification and as illustrated in the accompanying drawings in which:

Fig. 1 is a front elevational view of a hosiery mending apparatus embodying the invention.

Fig. 2 is a side elevational view of the left hand side of Fig. 1.

Fig. 3 is an enlarged section on line 3—3 on Fig. 1.

Fig. 4 is section on line 4—4 of Fig. 3.

Fig. 5 is a fragmentary sectional view showing certain details of structure.

The machine shown in the drawings includes a table top or working platform 10 which is suitably supported on a bent pipe frame 12. On the platform 10 is suitably mounted an elongated

anvil 14 which is so shaped that a stocking can be pulled over it as shown in Fig. 4. The anvil 14 has a smooth finish so as to guard against snagging and, on its upper side, it is provided with a recess for receiving a pad 16 detachably seated in said recess. The pad 16 is formed of any suitable core which is covered by a tough, heat-resistant, but smooth fabric for a purpose hereinafter fully explained. The upper working surface of the pad slopes downwardly in all directions so as to prevent marking the fabric. In other words, if the vertical sides of the pad are sharply squared with its upper working surface, a mark will be left on a fabric pressed against the pad. This sloping is shown at 18.

The table 10 also supports a vertical yoke or bracket 20 to the upper portion of which is pivoted, as at 22, an arm 24. The rear end of arm 24 is biased downwardly by a spring 26 the tension of which is adjusted by a conventional nut and bolt arrangement such as that shown in Fig. 3. The arm 24 is pivotally connected, as at 28, to the upper end of an operating rod 30 the lower end of which is pivoted at 32 to a treadle 34. The treadle 34 is pivoted at 36 to the frame 12 of the machine, so that when the front end 40 of the treadle is depressed, the rod 30 pulls the front portion of the arm 24 downwardly against the tension of the spring 26.

The front end of the arm 24 is provided with a hollow head 44 in the lower portion of which is detachably mounted a sole plate 42 by means of bolts, or the like, engaging lugs on the upper side of the sole plate and passing thru side walls of the head, as best shown in Fig. 3. The underside of the sole plate slopes gently upwardly in all directions, as shown at 46, so as not to leave a mark on the fabric placed on the pad 16 and subjected to pressure by the sole plate, in the manner and for the purpose hereinafter set forth.

The sole plate is heated by any suitable electric element which is energized by wires 48 leading from a source of electric energy. An indicating light 49 and a switch 50 are connected to the source of electric energy in series with the heating element.

The temperature of the sole plate is governed by a thermostat 52, located within the head 44 and adjustable to a position in which it will maintain the sole plate at the desired temperature, and which is subsequently locked in that position. The thermostat is connected to the electric circuit in series with the switch.

In order to prevent override in the temperature of the sole plate, either way, the top 54 of the

portion of the head 44 which houses the thermostat 52 is left open as shown in Figs. 4 and 5. By this arrangement, and by placing the thermostat directly on the sole plate, the temperature of the latter is held constant between close and rather critical limits. For example, it was found that, if the thermostat was wholly enclosed by the head in which the sole plate is mounted, it did not cool off in time to energize the heating element of the sole plate and the temperature of the latter dropped below the desired value. Conversely, if the thermostat was subjected to ambient temperatures, it energized the heating element of the sole plate prematurely and the temperature of the latter rose above the predetermined value.

The arm 24, the spring 26, and the sole plate 42, are enclosed by a fixed and attractive casing 56 which conceals all working parts except the switch and the indicating light. Also, the movement of the arm 24 is so arranged that, when the machine is at rest the front end of the arm, and, hence, the sole plate will be raised to a position in which the bottom of the sole plate is flush with or is slightly above the lower edge 58 of the front portion of the casing 56. This prevents accidental contact with the heated sole plate and protects its smooth, lower, working surface from injury. When the front end 40 of the treadle 34 is depressed, the front end of the arm 24 moves downwardly so as to bring the underside of the sole plate into contact with the pressure pad 16, and when the pressure on the treadle is relieved the spring 26 raises the front end of the arm 24 and moves the sole plate into its upper concealed position.

When it is desired to use the apparatus, the switch 50 is turned on and, when the sole plate has been heated to the predetermined temperature, the operator spreads the damaged portion of the fabric over the pressure pad 16 and depresses the treadle to cause the sole plate to apply heat and pressure to the fabric. If a stocking is to be so treated, it is drawn over the anvil until the damaged portion comes to rest over the pressure pad 16.

The amount of pressure to be applied and the length of time during which pressure is applied can be determined by the operator according to the nature and extent of the damage to be repaired and according to the denier of the yarn from which the fabric is made. However, by limiting the downward movement of the front end of the treadle, as shown in Fig. 2, the downward movement of the sole plate is also limited so that it will not exert excessive pressure on the fabric regardless of the pressure exerted by the operator on the treadle.

In order to facilitate operation, the machine is provided with one or more arms, on each of its opposite sides, for supporting the stockings

before and after they are mended. For example, on the right and left hand sides of the machine, as viewed in Fig. 1, the machine is provided with two arms 60 and 61, respectively. The arms 60 and 61 are provided with sleeves 62 which are freely rotatable about the legs or upright members 64 of the frame 10, the sleeves being prevented from slipping down on said legs by means of set screws or the like 66. When the machine is in use, the arms 60 and 61 are swung outwardly so as to project at an angle to the planes of the sides of the machine. In this position the arms extending from one side of the machine can be used for supporting the stockings to be mended and the arms on the other side of the machine can be used to support the stockings that have been mended. When the machine is not in use, the arms 60 and 61 are folded underneath the platform 10 so as to be out of the way.

What I claim is:

Apparatus of the character described which apparatus includes a frame, a table top carried by said frame, a fixed anvil located above the table top and having an upper, smooth working surface, a rocker arm carried by said table top, a heat and pressure applying head having a lower, smooth, working surface and carried by one end of said arm in vertical registration with said anvil, means for normally retaining said end of said arm and said head spaced upwardly from said anvil, means for actuating said arm to bring the working surface of said head into limited pressure contact with the working surface of said anvil, means for heating said head, a thermostat within said head, said head having a ventilating opening in the upper portion thereof, and a fixed casing carried by said table top and adapted substantially to enclose said arm and said head when the latter is in its upper position, the peripheries of said working surfaces sloping away from the plane of contact of said surfaces.
